UNITED STATES PATENT OFFICE.

OTTO WIEDEKE, OF DAYTON, OHIO, ASSIGNOR OF ONE-HALF TO GUSTAV WIEDEKE, JR., OF DAYTON, OHIO.

TUBE-CUTTER.

1,357,367.

Specification of Letters Patent.

Patented Nov. 2, 1920.

Application filed March 22, 1920. Serial No. 367,694.

To all whom it may concern:

Be it known that I, OTTO WIEDEKE, a citizen of the United States, residing at Dayton, in the county of Montgomery and State 5 of Ohio, have invented certain new and useful Improvements in Tube-Cutters, of which the following is a specification.

This invention relates to new and useful improvements in boiler tube cutters and is 10 an improvement of the boiler tube cutter shown and described in the patent to Gustav Wiedeke, No. 778,293, of Dec. 27, 1904.

The primary object of the present invention is to provide a tube cutter which is 15 suitable for the heaviest class of work. Another object is to provide means which serves to prevent the cutter breaking through the tube and damaging the tool and tube when said tool is forced. Another object is 20 to provide an adjustable indicator, instrumental in determining when the cutting operation is finished. And still another object is to provide an improved form of support or bearing for the roller cutters.

25 Referring in general terms to the accompanying drawings; Figure 1 is a side elevation of my improved tube cutter; Fig. 2 is a longitudinal sectional elevation thereof on the line 2—2 of Fig. 3; Fig. 3 is a section thereof on the line 3—3 of Figs. 1 and 2; Fig. 4 is a plan view of a portion of the tool showing the "pilot" cutter; Fig. 5 is a similar view showing the "follower" cutter; Fig. 6 is a plan view of one end of the tool showing 30 the adjustable indicator; Fig. 7 is an end elevation of the tool; Fig. 8 is an end elevation of one of the rotary cutters and its support; Fig. 9 is a perspective view of the bearing pins for the roller cutters; and Fig. 40 35 40 45 50 55 60 65 70 75 80 85 90 95 100 105 110

Throughout the specification and drawings, similar reference characters indicate corresponding parts.

45 Referring more particularly to the drawings, the tool is provided with a body having a front cylindrical portion —1—, an intermediate housing —2—, and a rear cylindrical portion —3— with a reduced extension —4—. The body of the tool is hollow and, mounted within the same, is a wedge or expanding member —5—. The said wedge —5— is inserted within the tool through an opening —6— in the cylindrical portion —1—. The opening —6— is closed, when

the tool is completely assembled, by a sleeve —7— held in position by a guide —8— attached to the body portion of the tool by a stud bolt —9—. The guide —8— is also instrumental in centering the forward end 60 of the tool in the tube. In addition to the guide —8—, the tool is centered by lugs —42— which extend from the intermediate housing —2—. One of the lugs may be provided with an anti-friction roller —43—. 65 The wedge —5— actuates carriers —10— and —11— that are movable in guide slots —12— and —13— in the intermediate housing —2—. The carriers are provided with inclined surfaces in engagement with the 70 wedge —5— whereby the said carriers and cutters move radially outward when the wedge —5— is moved in an expanding direction. The wedge —5— is provided with a recess which receives a flanged plate 75 —14— which cooperates with suitable grooves in the carriers to move said carriers inwardly when the wedge is moved in a contracting direction. The body portion is provided with a pin —45— lying in the 80 path of a lug —46— and which prevents the wedge moving to the right to a position to disengage the said wedge from the carriers.

The carriers —10— and —11— are provided with cutters —15— and —16— which sever the tube when the carriers are moved outwardly and the tool is rotated. In operation, the left end of the tool is inserted in a tube —17— as shown in Fig. 2 and the extent of insertion is limited by a cylindrical guard —19—. The said guard —19— is mounted on a sleeve —20— which is slidably supported on the cylindrical body portion —3—. The guard —19— is adapted to remain stationary when the body of the tool and the sleeve —20— rotates, the guard being attached to the sleeve through the agency of a screw —21— and annular groove —22—. The free end of the guard engages the tube sheet —18—, and the point at 100 which the tube is to be severed, and the position of the cutters relative to the tube sheet, are controlled by the guard —19—. In Fig. 2 the tool is set to sever the tube at a point, on the outside of the sheet, which permits the end of the tube to be subsequently "beaded." The tool may, however, be set to sever the tube at other points, by relocating the guard, for example, when it is desired to cut the tube on the inside of the 105 110

sheet —18—, prior to its removal from the boiler.

The tool is rotated by means of a ratchet —23— mounted on the reduced extension —4— and keyed to the body of the tool by lugs —44—. (Fig. 1.) The ratchet is engaged by a spring controlled pawl —24— mounted on a lever —25—. The lever —25— is freely mounted on the extension —4— and is held thereon by a collar —26—. The said lever —25— is also provided with a threaded end —27— adapted to receive the end of a pipe or handle —28—. By oscillating the handle —28— and lever —25— the tool is intermittently rotated. To move the wedge —5— to the right or in an expanding direction, the said wedge is provided with a rod —29— having a threaded end —30— which is received by a nut —31— in engagement with the end of tool. The nut —31— is rotated relative to the body portion of the tool, by a bifurcated handle —32— pivotally attached to the nut by means of trunnions —33—. The handle —32— may be moved with the lever —25— through the agency of a pin —34— extending from the lever —25— and lying in the path of the handle —32— when the handle lies at a right angle to the tool. When it is desired to rotate the nut —31— to shift the wedge —5— and to move the cutters outward whereby they may cut deeper, the handle is rocked out of the path of the pin —34— and is revolved independent of the remaining portions of the tool. As the cutting operation progresses the threaded end —30— moves out of the nut —31— and the amount of protrusion indicates the position of the cutters. To indicate when the cutters have reached a position which completes the cutting operation, the handle —32— is provided with a yoke —35—, which in turn is provided with an adjustable stop —36— in the form of a screw which lies in the path of the threaded end —30—. When the threaded end —30— comes in contact with the said adjustable stop, the operator will then know that the cutting operation is completed. Owing to the stop —36— being adjustable, the tool may be set to cut tubes of various gages.

In order to prevent the tool working out of the tube during the process of cutting, the "pilot" cutter —15— is set at an angle as shown in Fig. 4, in which view the angular disposition of the cutter is shown exaggerated to facilitate illustration. The said pilot cutter —15— directs the tool inwardly, which movement is resisted by the guard —19—, with the consequence that a true groove is cut without any tendency to form a thread or spiral race. The cutter —16— or "follower" is set at a right angle with the axis of the tool and follows in the groove

formed by the pilot cutter. The side faces 65 of the cutters —15— and —16— are convex to strengthen them. The "follower" cutter is narrower than the "pilot" cutter, and is therefore, sharper and will perform a greater amount of the cutting operation. The pilot 70 cutter being heavier, will be able to bear the extra burden placed thereon due to the cutter being placed at an angle, as the groove cut thereby is of greater width than the profile of the cutter. The pilot cutter, being 75 the heavier, forms the bead or flange —38— produced in the cutting operation, and being placed at an angle, snaps off the end of the tube, when the tool is severing the tube on the outside of the tube sheet. Owing to 80 the "follower" cutter —16— being the sharper, it will push its way through the tube, if the tube has any soft spots. To prevent the tool sticking and any consequent breakage of the tool or tube under forced 85 operation, the "follower" cutter —16— is provided with extended hubs —37— and the height of the cutting edge of the cutter above the hub is made equal to the height of the rolled flange —38— produced during 90 the cutting operation, as shown in Fig. 10. The cutter cannot therefore, force its way through the tube to an extent that might cause injury to the tool. The hubs —37— also tend to expand and tighten the tubes in 95 the tube sheet. As the height of the cutting edge is equal to the height of the rolled flange, the tubes will be held in place by the scale and burr when the tubes are being cut on the inside of the tube sheet.

The cutters —15— and —16— are supported in the carriers —10— and —11— by means of pins —39—. To hold these pins stationary while the cutters revolve, the said pins are provided with plane or flattened 100 faces —40— (Fig. 8) which may be parallel with or inclined to the axis of the pins. The faces —40— are at one end of the pins and lie within the opening of the carriers provided to receive said pins. Directly 105 above the said faces —40—, the carriers are dented as at —41—, thereby forming a non circular opening which prevents the said pins rotating. This arrangement does not, however, prevent said pins being extracted 110 from the other end of the carriers to permit of the removal and insertion of the cutters —15— and —16—.

Having described my invention, I claim:

1. In a tube cutter, a body portion, a circular pilot cutter mounted in said body portion on an angle thereto and adapted to cut a pilot groove, a relatively thin circular follower cutter adapted to enter said groove and to perform a greater amount of the subsequent cutting operation, means for expanding said cutters, and means for rotating said body portion.

2. In a tube cutter; a body portion; a pilot cutter and a follower cutter mounted in said body portion; the axis of the pilot cutter being disposed at an angle to the axis 5 of the tool whereby the said pilot cutter is adapted to cut a pilot groove; said follower cutter being sharper than said pilot cutter; means adapted to expand said cutters; means for rotating said body portion; and a guard 10 on said body portion.

3. In a tube cutter; a body portion; a pilot cutter and a follower cutter mounted in said body portion; the axis of the pilot cutter being disposed at an angle with the 15 axis of the tool whereby said pilot cutter is adapted to cut a pilot groove; said follower cutter being sharper than said pilot cutter; the said follower cutter having hubs adapted to limit the penetration of the cutter; 20 means adapted to expand said cutter; means

for rotating said body portion; and a guard mounted on said body portion.

4. In a tube cutter; a body portion; a pilot cutter and a follower cutter mounted in said body portion; the axis of the pilot 25 cutter being disposed at an angle with the axis of the tool whereby said pilot cutter is adapted to cut a pilot groove, said follower cutter being sharper than said pilot cutter; said follower cutter having hub extensions; 30 the height of the cutting edge of the said follower cutter above the hubs, being approximately equal to the height of the flange rolled in the tube in the process of cutting; means adapted to expand said cutters; 35 means for rotating said body portion; and a guard mounted on said body portion.

In testimony whereof I affix my signature.

OTTO WIEDEKE.
